UNITED STATES PATENT OFFICE.

CHARLES H. SHAFFER, OF ROCKFORD, ILLINOIS, ASSIGNOR OF ONE-HALF
TO JONES, WOODRUFF & CO., OF SAME PLACE.

FIRE-EXTINGUISHER.

SPECIFICATION forming part of Letters Patent No. 367,323, dated July 26, 1887.

Application filed September 20, 1886. Serial No. 214,071. (No model.)

To all whom it may concern:

Be it known that I, CHARLES H. SHAFFER, a citizen of the United States, residing at the city of Rockford, in the county of Winnebago and State of Illinois, have invented a new and useful Improvement in Fire-Extinguishers, of which the following is a specification.

This invention relates to automatic fire-extinguishers known as the "dry-pipe system," 10 employed mainly in buildings, and in which a system of pipes are distributed through the building to supply water when required, and in which automatic sprinklers controlled in their operation by heat are connected with 15 the water-distributing pipes at proper intervals. Its object is to render this class of fire-extinguishers more efficient, and for this purpose I employ electro-magnetism in the form known as the "closed electric circuit."

20 This application of electro-magnetism in connection with the dry-pipe system and its construction and operation will be hereinafter more fully described.

In the accompanying drawings, Figure 1 is 25 an elevation of portions of a fire extinguishing apparatus embodying my invention, and sufficient to illustrate its construction and application. Fig. 2 is an elevation, partly in section, showing the position of some of the 30 parts when the electric circuit is broken; and Fig. 3 shows the line-wire in its supports on the pipes in isometrical view.

In the figures, 1 represents a supply-pipe intended to connect with the water-supply. This 35 supply-pipe 1 is provided with a valve, 2, to close the end of the pipe against the pressure of the water. The valve 2 in this instance is of disk form, with its stem supported in a stuffing-box, 3, and is held to its seat by toggle-levers 40 4 and 5, which connect the projecting end of the valve-stem with a vertical yoke, 6, rising from the stuffing-box. The arm 5 of the toggle-levers is produced in bell-crank form, having a horizontal lever-arm, 7, supporting a 45 weight, 8, employed to flex the toggle-joint and lift the valve from its seat or permit it to rise under the pressure of the water. A set-screw, 9, is employed to control the position of the toggle-joint connection of the toggle-levers to limit them in their adjustment 50 substantially to a line relatively with their

pivotal connection. A connecting-rod, 10, is pivotally connected at its lower end to the free end of the weighted lever-arm 7, from which it rises through an insulated opening in 55 the free end portion of a circuit-closing spring, 11, fixed to the case 12, inclosing the magnets, and its upper end is fitted to engage a trip-lever, 13, having a pivotal connection with the magnet-case. 60

The free end of the trip-lever 13 engages the hook-latch end of an armature, 14, pivoted in position to engage the pole ends of the electro-magnets 15, supported in the case 12. An adjustable spring, 16, is employed to carry the 65 armature from the magnets when the electric circuit is broken, and an adjusting-screw, 17, is employed to limit the outward movement of the armature.

The connecting-rod 10 is provided with a 70 tappet-stop, 17½, to engage the insulating-bushing forming the opening in the free end of the circuit-closing spring 11, to cause it to descend with the downward movement of the rod and engage the free end of the circuit-closing arm 18, fixed to the magnet-case, for a purpose hereinafter to appear. By this construction and arrangement of the parts the connection of the trip-lever with the connecting-rod and with the armature, as shown in 75 Fig. 1, with closed circuit, will hold the valve to its seat and prevent the escape of water from the supply-pipe; and with broken or open circuit the armature will be liberated, and the spring-action will disengage it from 80 the trip-lever, which will permit the weight to carry the parts to their position, (shown in Fig. 2,) open the valve, and permit the water to flow from the supply-pipe.

A system of water-distributing pipes is 85 connected with the water-supply pipe, and may be distributed through the building in which the apparatus is employed to any extent required. In this instance distributing-pipes sufficient to illustrate the application 90 and working of the apparatus are employed, and consist of a horizontal pipe, 19, connecting the supply-pipe with a vertical pipe, 20, provided with an outlet-valve operated by the hand-wheel 21, fixed on the projecting end of 100 its valve-stem. A horizontal distributing-pipe, 22, is connected with the vertical pipe,

and is designed to be fixed to the under face of the ceiling of the apartment in which it is employed or suspended therefrom in any suitable manner. This distributing-pipe 22 is provided at proper intervals with sprinklers 23, which may be any of the known varieties capable of use in connection with my improved apparatus; but I prefer my improved sprinkler shown, described, and claimed in my application for patent executed August 21, 1886, now on file in the United States Patent Office and pending office action. Of this sprinkler I do not deem a detailed description necessary in this application, further than that the sprinkler employed is held in position to exclude the water by means of a two-part clasp-bar, 24, having a solder-connection capable of separating at a low temperature to admit the water to the distributing apparatus 20 of the sprinkler.

An electric battery, 25, which may be any of the known varieties best adapted for closed-circuit purposes, and may be located at any convenient point relatively with the electro-magnets 15, is employed. The battery 25 is connected by connecting-wires 26 to the electro-magnets 15 and to the system of water-pipes through the medium of the trip-lever 13, which in its connection with the valve 30 mechanism communicates with the water-pipes. The battery is also connected with the water-pipes by a line-wire, 27, extending to or beyond the sprinkler farthest from the battery on the line of the pipes, at which point 35 it connects with the pipes, forming a complete outgoing and return circuit. The line-wire in this instance is supported in insulating-brackets 28, fixed to the pipe preferably at or near the sprinklers, and within the bracket 40 supports the line-wire has a solder-connection, 29, of a low-melting temperature.

With the several parts of my improved fire-extinguishing apparatus constructed and applied substantially as shown and described 45 heat produced from fire within the vicinity of the sprinklers, or any one or more of them, will melt the solder joining the two parts of the clamp-bar 24 and permit the valve in the sprinkler to open. The heat will also melt 50 the solder employed to connect the line-wire, break the electric circuit, demagnetize the electro-magnets, release the armature, and permit the 55 weight to descend, open the valve, and admit the water to the system of pipes to be discharged through the open sprinkler or sprinklers.

An electro-magnetic alarm-bell, 30, of any 60 of the usual constructions capable of use in connection with my improved fire-extinguishing apparatus and located in any convenient or desirable position, is electrically connected with the battery by means of a wire, 31, passed 65 from its connection with the battery to connect with the electro-magnets of the alarm-bell, and terminating in its connection with

the circuit-closing arm 18, fixed to the magnet-case.

A branch-wire, 32, is employed to connect to the spring circuit-closer 11 with the wire 26, employed to connect the magnets 15 with the battery in such a manner that if from any cause the circuit controlling the opening of the valve 2 to the water-supply pipe should 75 be broken the opening of the valve will cause the spring circuit-closer 11 to engage the circuit-closing arm 18, as shown in Fig. 2, complete the electric connection through the alarm-bell, and cause it to ring, giving notice of the 80 opening of the electric circuit controlling the valve to the water-supply. In this construction and arrangement of the parts the breaking or opening of the electrical circuit controlling the valve to the water-supply operates to close 85 the circuit to the alarm-bell automatically, and the closing of the circuit controlling the valve to the water-supply opens or breaks the circuit to the alarm-bell.

In adjusting the apparatus for use the valve 90 to the water-supply is closed and the parts adjusted to close the electric circuit to hold it in its closed position. The water is then drawn from the distributing-pipes by means of the outlet-valve, after which it is closed. The 95 sprinklers are then adjusted and their valves closed, which fits the apparatus for use.

I claim as my invention—

1. In a fire-extinguisher, the combination, 100 with a water-supply pipe, water-distributing pipes connected therewith, and a valve to control the admission of the water to the distributing-pipes, of a normally-closed electric circuit, an electro-magnet within the closed circuit, and a lever having the weighted arm of 105 a valve-controlling lever suspended from its short arm and the armature of the magnet in engagement with its long arm, whereby the valve is held closed when the armature is in contact with the pole of the magnet, substantially as set forth.

2. In a fire-extinguisher, the combination, 110 with a water-supply pipe, water-distributing pipes connected therewith, and a valve to control the admission of water to the distributing-pipes, of a normally-closed electric circuit, an electro-magnet within the closed circuit, and a lever having the weighted arm of a valve-controlling lever detachably suspended from its short arm and its long arm in engagement 120 with a shoulder or hook on the armature of the magnet, whereby the valve is held closed when the armature is in contact with the pole of the magnet and allowed to open when the armature is withdrawn from the pole, substantially as set forth.

3. In a fire-extinguisher, the combination, 130 with the normally-closed electric circuit made separable by the action of heat, the valve for admitting water to the distributing-pipes, and an electro-magnet within the closed circuit, of an electric alarm, a stationary arm electrically connected with the alarm, and a spring-arm having its free end in engagement with a mov-

able section of the valve-controlling mechanism and adapted to engage the said stationary arm when the valve is opened and form an electric circuit through the battery and alarm, substantially as set forth.

4. The combination, with the water-supply pipe and with the distributing-pipes connected therewith, of a valve, toggle-lever mechanism for operating the valve, the electro-magnet, and the connection between the armature of the magnet and the toggle-lever mechanism, whereby the admission of water to the distributing-pipes is controlled by the breaking of the electric circuit, substantially as set forth.

15 5. The combination, with the weighted arm of the toggle-lever mechanism to the valve and with the armature to engage the poles of the magnets, of a trip-lever and rod-connection of the armature with the weighted arm of the toggle lever mechanism, substantially as and for the purpose set forth.

6. The combination of the trip-lever mechanism connecting the armature with the weighted arm of the toggle-lever mechanism 25 of the valve, electro-magnets electrically connected with the trip-lever mechanism and with the battery, and a line-wire connecting the battery with the water-supply pipes completing the electric circuit, said circuit having solder-connections fusible at a low temperature, substantially as and for the purpose set forth.

7. The combination, with the normally-closed electric circuit, the supply and the distributing pipes, of the sprinkler secured to the 35 distributing-pipe, and the insulating wire-supporting bracket attached to the distributing-pipe in a position near the sprinkler, for the purpose substantially as set forth.

8. The combination, with the distributing-pipes in a normally-closed electric circuit, with a magnet, and with mechanism for controlling a supply-valve, of solder-closed sprinklers secured to the distributing-pipes, insulating

wire supports attached to the distributing-pipes near the sprinklers, and solder-connections joining the wire near the bracket-support, whereby the heat which separates the wire at the solder-connection will open the solder-closed sprinkler nearest thereto, substantially as set forth.

45 9. The combination, with the water-distributing pipe in a normally-closed electric circuit and a wire having solder-connections fusible at a low temperature, the wire being attached to the distributing-pipe by insulating-brackets, of a sprinkler connected with the distributing-pipe, said sprinkler being provided with a solder-connection fusible at a low temperature to liberate the sprinkler, substantially as set forth.

50 10. The combination, with the rod connecting the weighted arm of the toggle-levers, with the trip-lever, and with the circuit-closing arm to the alarm-bell, of a circuit-closing spring to engage the circuit-closing arm, substantially as and for the purpose set forth.

55 11. The combination, with the supply-valve and the toggle-levers for operating the valve, of the set-screw for regulating the adjustment of the levers in line with their pivotal connections, substantially as set forth.

60 12. The combination, with the normally-closed electric circuit, the magnet within the circuit, and a water-supply valve held in closed adjustment by the armature of the magnet 75 when in contact with the pole, of a spring having an adjustable tension adapted to automatically release the armature of the magnet from the valve-controlling mechanism when the circuit is broken, and the set-screw for determining the throw of the armature, substantially as set forth.
